JOHN D. IHLDER, OF YONKERS, NEW YORK, ASSIGNOR TO OTIS ELEVATOR COMPANY, OF EAST ORANGE, NEW JERSEY, A CORPORATION OF NEW JERSEY.

MAGNETIC BRAKE.

SPECIFICATION forming part of Letters Patent No. 758,140, dated April 26, 1904.

Application filed September 2, 1903. Serial No. 171,649. (No model.)

To all whom it may concern:

Be it known that I, JOHN D. IHLDER, a citizen of the United States, residing at Yonkers, in the county of Westchester and State of New York, have invented certain new and useful Improvements in Magnetic Brakes, of which the following is a specification.

My invention relates to magnetic brakes. I will describe a magnetic brake embodying my invention and then point out the novel features thereof in the claims.

In the accompanying drawings, Figure 1 is a diagrammatical view of a magnetic brake embodying my invention and of circuits and 15 a circuit controller or controllers therefor. Fig. 2 is also a diagrammatical view of a magnetic brake embodying my invention and showing a different arrangement of circuits and a circuit controller or controllers therefor.

Similar characters of reference designate corresponding parts in both of the figures.

10 designates a rotating part which may be comprised in an operating mechanism. For example, it may be fixed on the armature-shaft 25 of an electric motor.

11 designates a brake, which may be of any suitable construction and which when applied to the part 10 tends to stop the part 10 from rotating. As here shown the brake 11 is in 30 the form of a shoe.

The brake 11 is adapted to be withdrawn or released from and held from engagement with the part 10 by electromagnetic means, and the electromagnetic means is preferably adapted 35 when deprived of its exciting-current to permit of the brake being gradually applied to the part 10. The electromagnetic means is preferably in the form of an electromagnet of the plunger type.

40 22 designates the exciting-coil of the electromagnet, which in practice is wound upon a spool or bobbin, and 20 a metallic frame in which the exciting-coil is arranged. The metallic frame 20 is of such shape and arrangement as to provide a closed or a substantially closed magnetic circuit. The core of the magnet is divided. One part, 21, is connected with the frame 20 or it may be integral with

the frame, while the other part, 21, moves in and out of the exciting-coil. The part 21 is 50 joined by a connection 12 with the brake 11, and a spring 13, here shown as being a spiral spring and as surrounding the connection 12, is provided between the brake 11 and some fixed part—for example, the frame 20. 55

A and B designate conductors leading from some source of electrical supply, and 81 82 two conductors leading from the conductors A B to the terminals of the exciting-coil 22. Included in the circuit of the exciting-coil in 60 Fig. 1 is a resistance 80 and a suitable form of circuit-controller, here shown as being in the form of a switch 50, movable into and out of engagement with a contact 51, also included in the circuit. 65

83 designates a conductor which is joined to the conductor 81 in two places in such manner as to bridge the resistance 80, and it is also joined to the conductor 82. Included in the conductor 83 are two circuit-controllers 70 30 40, here shown each as being in the form of a switch. The circuit-controller 30 is adapted to be moved into and out of engagement with a contact 31, included in the conductor 83, and the circuit-controller 40 is 75 adapted to be moved into and out of engagement with a contact 41, also included in the conductor 83. It will be seen that when the circuit-controllers 30 and 50 are moved into engagement with their respective contacts 31 80 and 51 current from the conductors A B will flow directly through the exciting-coil 22, which will then draw the part 21 of the core within it, and thus withdraw the brake 11 from the part 10 against the action of the 85 spring 13, which always acts to apply the brake 11. The current from the conductors A B will not entirely flow through the resistance 80, owing to the conductor 83 offering less resistance to the passage of the current. 90

After the brake has been withdrawn from the part 10 the circuit-controller 30 may be moved to open the circuit just described, and the current from the conductors A B will then be supplied the exciting-coil 22 through the resistance 80. The purpose of bringing the

resistance into the circuit at this time is to save current, for as soon as the magnetic circuit is established through the frame 20 and the two parts of the core which are drawn 5 toward each other less current is required to hold the part 21 within the exciting-coil than is required to draw the part 21 into the exciting-coil. When the brake is to be applied, the circuit-controller 40 is moved into engagement with the contact 41 and the circuit-controller 50 preferably moved out of engagement with the contact 51. This operation of the circuit-controller causes the exciting-current to be short-circuited from the exciting-coil if the circuit-controller 50 is not operated or the exciting-current interrupted if the controller 50 is operated. As soon as either of these operations occur there will be a decrease of the magnetic flux. The operation 10 of the circuit-controller 40, however, establishes a closed circuit for the exciting-coil, and as the magnetic flux decreases it induces a current in the exciting-coil which tends to build up the decreasing magnetic flux. In 15 this way a slow and gradual application of the brake 11, under the influence of the spring 13, is obtained.

Referring now to Fig. 2, it will be seen that I employ an additional winding 23 on the exciting-coil and provide in this winding a circuit-controller 60, here shown as being in the form of a switch which is movable into and out of engagement with a contact 61. This circuit-controller is adapted to open and close 20 the circuit for the winding 23. If desired, this circuit-controller may be omitted entirely and the circuit always be a closed one. In this figure the controller in the circuit of the exciting-coil is designated 70, and, as 25 shown, is in the form of a switch movable into and out of engagement with a contact 71. In this form when the brake is to be withdrawn from the part 10 the circuit-controller 70 is first operated to close the circuit of the exciting-coil, and the circuit-controller is left in such position 30 as to always keep this circuit closed so long as the brake is to be held out of engagement with the part 10. When the brake is to be applied, the circuit-controller 60 is first operated to 35 close the circuit for the coil 23 and the circuit-controller 70 then operated to open the circuit of the exciting-coil. The opening of the circuit of the exciting-coil will cause a decrease in the magnetic flux, and this decrease 40 will induce a current in the coil 23, which tends to build up the decreasing magnetic flux and to retard the movement of the part 21 out of the exciting-coil, thereby obtaining a slow and gradual application of the brake. 45 In this form of the invention the circuit-controller 60 may be first operated to close the circuit of the coil 23 before the circuit-controller 70 is operated, and then the brake will be withdrawn slowly, because of the choking effect of the coil 23. If it is desired to

apply the brake quickly, the circuit-controller 60 may be opened before the circuit-controller 70. If the coil 23 is permanently closed, the movement of the part 21 is sluggish in both directions.

It will be understood that I do not limit myself to the precise arrangement of circuits shown in Fig. 1 nor to the precise arrangement and form of the circuit-controllers, all of the circuit-controllers may be comprised 75 in a single device which may be so arranged that upon its operation the current will first be supplied to the exciting-coil to withdraw the brake, and after the withdrawal of the 80 brake the resistance will be brought into the circuit, and finally when the brake is to be applied the circuit of the exciting-coil may be either interrupted or short-circuited and the exciting-coil closed upon itself. In Fig. 85 2 the two circuit-controllers may also be included in a single device and operated successively to accomplish the results hereinbefore stated.

It will be seen, therefore, that my invention 90 consists of electromagnetic means for operating a brake, which electromagnetic means comprises devices by which an induced current is generated when the exciting-current for the electromagnetic means is supplied or cut off from it, which induced current tends 95 to choke or build up the increasing or decreasing magnetic flux of the electromagnetic means and permit of a slow and gradual operation of the brake.

What I claim as my invention is—

1. An electromagnetic brake having means operated by the magnetic flux for effecting a slow action of the brake.
2. In an electromagnetic brake, an exciting-coil for moving the brake in one direction and electromagnetic means which upon the deenergizing of the coil permits of a gradual action of the brake in an opposite direction.
3. In an electromagnetic brake, an exciting-coil for releasing the brake, and electromagnetic means which upon the deenergizing of said coil permits of a gradual application of the brake.
4. In an electromagnetic brake, the combination of an exciting-coil and a magnetic circuit comprising a movable part which is connected with a brake, a source of current-supply for said exciting-coil which coil, when excited, produces magnetic influx in said magnetic circuit to operate said movable part, and means which, upon the deenergizing of said exciting-coil, tend to build up the decreasing magnetic flux produced by deenergizing said exciting-coil, whereby a gradual action of said part is obtained.
5. In an electromagnetic brake, the combination of a coil for operating the brake, and another coil for effecting a slow action of the brake.
6. In an electromagnetic brake, the combi- 130

nation of a coil for operating the brake, and another coil for effecting the slow action of the brake in either direction.

7. The combination in an electromagnetic brake of an electromagnet for operating the brake, said electromagnet comprising exciting-coils and a magnetic circuit which latter excites a current in one of the coils upon a cessation of current in another.

10 8. The combination in an electromagnetic brake, of an electromagnet for operating the brake, said electromagnet comprising exciting-coils and a magnetic circuit which includes a movable part, and which excites a current in one of the coils upon a cessation of current in another.

9. The combination in an electromagnetic brake, of an electromagnet for operating the brake, said electromagnet comprising exciting-coils and a magnetic circuit which latter excites a current in one of the coils upon a cessation of current in another, and means for controlling the circuit of said exciting-coils.

10 10. The combination in an electromagnetic brake, of an electromagnet comprising exciting-coils, and a movable part which is con-

nected with the brake, said exciting-coils being adapted, one to withdraw the brake and another to retard the application of the brake.

11. The combination in an electromagnetic 30 brake, of an electromagnet comprising exciting-coils, and a movable part which is connected with the brake, said exciting-coils being adapted, one to withdraw the brake and another to retard the application of the brake, 35 and means for controlling the circuits of said exciting-coils.

12. The combination in an electromagnetic 40 brake, of means for moving the brake to apply it, and an electromagnet for moving the brake to withdraw it, said electromagnet comprising exciting-coils, which are adapted one to withdraw the brake and another to retard the application of the brake by said applying means.

In testimony whereof I have signed my name to this specification in the presence of two subscribing witnesses.

JOHN D. IHLDER.
